UNITED STATES PATENT OFFICE.

JACOB KAPPLER, OF PHILADELPHIA, PENNSYLVANIA, ASSIGNOR TO GILL & COMPANY, OF PHILADELPHIA, PENNSYLVANIA, A CORPORATION OF PENNSYLVANIA.

DESIGN FOR A LAMP SHADE OR REFLECTOR.

40,920.

Specification for Design.

Patented Sept. 27, 1910.

Application filed August 17, 1909. Serial No. 513,365. Term of patent 14 years.

To all whom it may concern:

Be it known that I, JACOB KAPPLER, a citizen of the United States, residing at Philadelphia, in the county of Philadelphia and State of Pennsylvania, have invented a new, original, and ornamental Design for a Lamp Shade or Reflector, of which the following is a specification, reference being had to the accompanying drawing, forming part thereof.

Figure 1 is a side view in elevation of a lamp shade or reflector showing my new design. Fig. 2 is a top plan view.

The shade has an external surface ornamented with beaded prisms, said prisms ex-

tending from adjacent the collar at the top to positions adjacent the lower edge of the shade. The beads are in a row, located at the line of the meeting surfaces of a prism, and project from said line. The characteristic feature of the ornamentation is the beaded prisms.

I claim:

The ornamental design for a lamp shade or reflector, as shown and described.

JACOB KAPPLER.
